His Attorney.

UNITED STATES PATENT OFFICE

CHRISTIAN STEENSTRUP, OF SCHENECTADY, NEW YORK, ASSIGNOR TO GENERAL ELECTRIC COMPANY, A CORPORATION OF NEW YORK

CONDENSER FOR REFRIGERATING MACHINES

Application filed August 26, 1931. Serial No. 559,520.

My invention relates to air-cooled condensers for refrigerating machines.

It has generally been the practice, heretofore, to use piping or tubing of coil shape or zigzag form for the condenser of refrigerating machines. In such condensers the refrigerant flowing through the piping is cooled and condensed by the circulation of air, which is induced either by forced or natural draft.

The object of my invention is to provide an improved condenser of this type having a fluid passageway provided with a heat dissipating surface for effectively cooling and condensing the refrigerant flowing through the passageway.

Further objects and advantages of my invention will become apparent as the following description proceeds, and the features of novelty which characterize my invention will be pointed out with particularity in the claims annexed to and forming a part of this specification.

For a better understanding of my invention, reference may be had to the following description taken in connection with the accompanying drawings in which Fig. 1 is a front elevation, partly in section, of a refrigerating machine embodying my invention, and Fig. 2 is a perspective view of parts of Fig. 1.

Referring to the drawings, I have shown my invention in connection with a compression refrigerating machine of the general construction described in my United States Letters Patent No. 1,736,635, granted November 19, 1929 to the same assignee as this invention. This machine comprises a motor and compressor arranged in a vertical refrigerant containing casing 1 which is mounted on a base plate 2 removably supported in an opening in a refrigerator cabinet 3. In this construction the compressed refrigerant gas is discharged from the compressor into the casing 1 and flows through a connection 4 into an air-cooled fluid passageway 5, which is arranged about a plurality of heat dissipating elements or cooling fins 6 secured to the casing 1 for cooling the refrigerant and removing the heat

from the casing 1 by the circulation of air induced by natural draft. The refrigerant is condensed in the passageway 5 and flows therefrom, under the control of a float valve indicated at 7, into an evaporator 8 supported by the base 2. The motor in the enclosing casing 1 is controlled in response to the temperature of the evaporator 8 by a thermostatic device 9.

In accordance with my invention a fluid passageway 5 forming the condenser is constructed in such manner that it cooperates with a strip of metal 10, which forms a heat dissipating surface for cooling the fluid flowing through the condenser. The passageway 5 is preferably made integral with the strip 10, although it may be secured thereto in any other suitable manner to form a unitary structure. I prefer to form the passageway 5 at one edge of the strip by folding over or bending the edge 11 upon itself and uniting it by a lap joint in any suitable manner, such as brazing or welding, to a portion of the strip as indicated at 12. The strip 10 with the passageway 5 is formed into a helical coil with the passageway 5 at the outer edge, and the inner edge 14 is secured into downwardly slanting notches 15 at the outer ends of the fins. One end of the fluid passageway is connected to the compressor casing as indicated at 4, and the other end thereof to the float valve 7.

In this construction, the helical strip 10 slopes downwardly from the inner to the outer edge, that is, it slopes downwardly in the direction away from the casing. The heat radiated from the casing 1 combined with the heat radiated from the condenser or passageway 5 causes sufficient upward flow of air by natural draft to cool the refrigerating machine during operation. By sloping the strip 10 downwardly in the direction away from the casing cool air is drawn from the air surrounding the condenser and passes upwardly between all of the spaces of the helical strip 10, as well as passing upwardly through the channels 16 formed by the fins 6 between the casing 1 and the helical strip 10. The natural draft of air thus passing over the condenser 5, the strip 10, the fins 6,

and the casing 1 efficiently cools the machine.

In this manner a condenser is obtained which can readily be made from a strip of metal. The strip of metal having a fluid 5 passageway at one edge thereof provides a rigid and durable condenser construction which can be formed to any shape desired, and the increased heat dissipating surface formed by the strip 10 effectively cools the 10 refrigerant flowing through the passageway.

Although I have shown my improved air-cooled condenser in connection with a compression refrigerating machine, I do not desire my invention to be limited to the particular arrangement set forth, and I intend 15 in the succeeding claims to cover all modifications which do not depart from the spirit and scope of my invention.

What I claim as new and desire to secure 20 by Letters Patent of the United States, is,—

1. A condenser for a refrigerating machine including a strip of metal provided with a fluid passageway at one edge thereof, said strip serving as a heat dissipating surface for 25 cooling the fluid flowing through said passageway.

2. A condenser for a refrigerating machine including a strip of metal having one portion thereof bent upon itself and united to an 30 other portion of said strip to form a fluid passageway, said other portion extending from said passageway to form a heat dissipating surface for cooling the fluid flowing through said passageway.

3. An air-cooled condenser for a refrigerating machine including a supporting member, a plurality of heat dissipating elements arranged about said supporting member, and a helical strip of metal arranged about said 40 heat dissipating elements and cooperating with a fluid passageway in heat exchange relation therewith, said helical strip being secured at the inner edge thereof to the outwardly extending portions of said heat dissipating elements in heat exchange relation therewith.

4. An air-cooled condenser for a refrigerating machine including a supporting member, a plurality of heat dissipating elements 50 arranged about said supporting member, and a helical strip of metal arranged about said heat dissipating elements and provided with a fluid passageway at the outer edge thereof, the inner edge of said helical strip being secured in heat exchange relation to the outwardly extending portions of said heat dissipating elements.

5. An air-cooled condenser for a refrigerating machine including a supporting member, a plurality of heat dissipating elements arranged about said supporting member, and a helical strip of metal having one portion thereof bent upon itself and united to another portion of said strip to form a 65 fluid passageway, the inner edge of said strip

being secured to the outwardly extending portions of said heat dissipating elements in heat exchange relation therewith.

6. An air-cooled condenser for a refrigerating machine including a supporting member, a plurality of heat dissipating elements arranged about said supporting member, and a helical strip of metal secured in heat exchange relation at the inner edge thereof to the outer ends of said fins and having the 75 outer edge thereof folded over and united to a portion of said strip to form a fluid passageway.

7. A refrigerating machine including a casing constituting a refrigerant chamber, a plurality of fins arranged about said casing, and a helical strip of metal arranged about said fins and cooperating with a fluid passageway in heat exchange relation therewith, said helical strip being secured in heat exchange relation at the inner edge thereof to the outer ends of said fins.

8. A refrigerating machine including a casing constituting a refrigerant chamber, a plurality of fins arranged about said casing, and a helical strip of metal arranged about said fins and provided with a fluid passageway at the outer edge thereof, the inner edge of said helical strip being secured in heat exchange relation to the outer ends of said fins.

9. A refrigerating machine including a casing constituting a refrigerant chamber, a plurality of fins arranged about said casing, and a helical strip of metal arranged about said fins and having one portion thereof bent upon itself and united to another portion of said strip to form a fluid passageway, the inner edge of said strip being secured to the outer ends of said fins in heat exchange relation therewith.

10. A refrigerating machine including a casing constituting a refrigerant chamber, a plurality of fins arranged about said casing, and a helical strip of metal secured in heat exchange relation at the inner edge thereof to the outer ends of said fins and having the outer edge thereof folded over and united to a portion of said strip to form a fluid passageway.

11. A refrigerating machine including a casing constituting a refrigerant chamber, a plurality of notched fins surrounding said casing, and a helical strip of metal having the outer edge thereof bent upon itself and united to a portion of said strip to form a fluid passageway, the inner edge of said strip being secured in heat exchange relation in the notches in said fins.

12. In a refrigerating machine, a casing, heat dissipating elements arranged about said casing, a helical strip of metal surrounding said casing having a fluid passageway forming a condenser at the outer edge thereof, said helical strip sloping downwardly

from the inner to the outer edge thereof and secured in heat exchange relation at the inner edge thereof to the outwardly extending portions of said heat dissipating elements.

5 13. A refrigerating machine comprising a substantially vertical casing, fins arranged about said casing, and a helical strip of metal arranged about said casing and provided with a fluid passageway at the outer 10 edge thereof, said helical strip sloping downwardly from the inner to the outer edge thereof and secured in heat exchange relation at the inner edge thereof to the outer ends of said fins.

15 In witness whereof, I have hereunto set my hand.

CHRISTIAN STEENSTRUP.
